UNITED STATES PATENT OFFICE.

CHRISTIAN H. KREILING, OF CHANDLERVILLE, ILLINOIS.

EXCAVATING APPARATUS.

1,009,532.

Specification of Letters Patent. Patented Nov. 21, 1911.

Application filed May 23, 1910. Serial No. 562,890.

To all whom it may concern:

Be it known that I, CHRISTIAN H. KREILING, a citizen of the United States, residing at Chandlerville, in the county of Cass and State of Illinois, have invented new and useful Improvements in Excavating Apparatus, of which the following is a specification.

My invention relates to excavating apparatus or dredging machines of the class especially employed for digging, deepening, or widening open ditches, ship-canals, etc.

One of the objects of my invention is to provide a power-driven machine which is capable of performing heavy work with great rapidity, and may be readily manipulated to change the relation of the several dipper-operating parts to suit the varying conditions of the work being performed.

To this end I provide a duplex-operating dipper or bucket which is constructed with doors upon opposite ends with locking devices so arranged that the bucket may be driven in either direction, thus practically doubling the working capacity of a single bucket operating in only one direction. To accommodate the excavator to the varying conditions of the work, I mount the dipper-beam or stem for universal movement and connect it operatively to opposite swinging booms.

The advantages of my excavating apparatus will be clearly understood from the following description in connection with the accompanying drawings, in which—

Figure 1 is a side elevation of my duplex-operating dipper; Figs. 2 and 3 are respectively end and top plan views of the same; Fig. 4 is an end elevation of my dredger or excavator; Fig. 5 is a side elevation of the dredger.

In the drawings, I have shown my apparatus mounted upon the frame of the usual power dredge, the steam-boiler, engine, and hoisting-drums being illustrated in a conventional manner. The booms B, B, which carry the hauling and hoisting cables f, connected to the dipper or bucket k, are pivotally mounted to swing horizontally about the central bearing plate H, and may be raised or lowered to different heights by means of the cables h passing over pulleys b and c. The beam or stem A, constituting the handle of the dipper k, passes through a universal bearing or ball-joint E carried

upon the outer end of the pintle support F, which is swiveled in the casting M, forming the head of the A-frame having legs C, firmly supported and braced in the skeleton frame of the dredge. The dipper-beam is, therefore, capable of universal movement about the pintle support F. The vertical adjustment of the dipper-beam A is controlled by means of the friction-wheels I, having a shaft carrying a pinion q which engages a rack L on the beam.

Attached to each boom B is a cable g, which runs on a winding drum N, and by means of which the booms may be separately swung forward or backward about the pivot block H. By throwing one boom forward and the other backward, the dipper or bucket k, may be caused to traverse a diagonal path instead of passing straight across a ditch.

When the dredge boat is to be moved forward to a new position, the two booms are swung forward, projecting directly in line with the boat, and a cable z is secured to a loop or hook on the dipper beam. By pulling upon both hoisting cables f, f, the dipper is thrown forward and dropped upon the ground. Then by pulling upon the cable z the boat is drawn forward. After the spuds or anchor-posts Z have been lowered, the booms are swung outwardly into operative position and the hauling cable z is unhooked.

The dipper or bucket k is pulled back and forth across the ditch by means of the hoisting cables f, f, attached thereto and passing over the pulleys e, on the booms B, to the winding drums G of the hoisting engine.

I employ a duplex-operating dipper or bucket capable of digging when moved in either direction, as will more clearly appear from the detail views shown in Figs. 1, 2, and 3. The dipper is open at both ends, and is provided with a plow or cutting edge Y and with doors P hinged at the top upon rods n. The doors may swing inwardly, but are locked against outward movement by the locking bolts T, which slide in guides V. In order to prevent the doors from swinging freely and thus interfering with each other, a counterweight w holds the door back into the dipper when it is starting to load, and a coil spring x prevents the door from swinging back in the way of the other door when loading. Without these restraining devices, it is evident that the doors might

interfere and block each other. The bolts T are beveled in a manner to prevent outward movement of the door. The upper end of the bolt is connected to a bell-crank lever R, mounted in bearings Q, which is connected by means of a chain or rod S, with a lug X on the pivot-boss of the bail O. During the digging or filling operation, the bolt T is held downward by the spring 10 U, but when the dipper has been raised to the position shown in dotted lines in Fig. 4, the lower bail will be swung upwardly, rocking the bell-crank lever R, withdrawing the bolt T, and permitting the door to swing 15 outward to dump the load.

In the operation of my dredging apparatus, the booms are swung to the desired position and the dipper is drawn alternately by the cables f, f, from one side of the ditch to 20 the other, the dipper being filled and dumping a load in each direction. The enormous advantages derived from the use of my duplex-operating dipper, loading or unloading at each forward or backward stroke, will be 25 appreciated by engineers. In order to provide for the most effective use of my double-operating dipper or bucket, I have devised the arrangement of double booms, each swinging independently about its pivot, 30 whereby one may be thrown forward of the other, causing the digging-member to traverse a diagonal path across the line of excavation, such movement being permitted by the universal movement of the pivotal 35 support of the dipper handle or stem. It appears, therefore, that each of the adjustable features of the dipper-operating mechanism co-operates to render effective the construction of my duplex-operating dipper.

40 While I have described in detail the construction of the dipper and operating mechanism disclosed herein, yet it is to be understood that many changes can be made therein without departing from the spirit of my 45 invention or the scope of my claims, which are—

1. An excavator-dipper having an inwardly and outwardly swinging hinged door mounted at each end and each provided with 50 detachable locking means for securing the door against outward movement.

2. An excavator-dipper having a hinged door at each end provided with detachable locking means for securing the door against 55 outward movement, and yielding means for restraining the inward movement thereof.

3. An excavator-dipper having an inwardly and outwardly swinging hinged door at each end provided with detachable locking 60 means for securing the door against outward movement, and means for disengaging

said locking means of the lower door when the dipper is turned into unloading position.

4. An excavator-dipper having an inwardly and outwardly swinging hinged door 65 at each end provided with detachable locking means for securing the door against outward movement, a bail pivotally mounted upon each end of the dipper and co-operating 70 with the adjacent door, and means connecting the bail with the locking means of the corresponding door.

5. An excavator-dipper having a hinged door at each end provided with a locking device for securing the door against outward movement, a counter-weight to maintain the door within the dipper at the beginning of the loading operation, and a yielding restraining device to prevent the door from 75 swinging into the dipper.

6. An excavator-dipper comprising a body portion open at each end, doors hinged upon either end to swing inwardly and outwardly, a locking device to prevent the outward movement, tripping mechanism for said locking device, and a bail pivoted to either end of the body and connected with said tripping mechanism.

7. An excavating machine comprising a reciprocating dipper-arm carrying upon its lower end a double-ended dipper, end closures for said bucket adapted to swing inwardly and outwardly and provided with detachable locking means, a support for said arm having a universal connection therewith, and a plurality of independently swinging booms, each adapted to swing both forwardly and rearwardly of said support and having operating mechanism connected with said bucket, whereby the dipper may 100 be reciprocated transversely or obliquely to said machine.

8. An excavating machine comprising a reciprocating arm, a double-ended dipper having end closures adapted to swing inwardly and outwardly, locking means for normally securing the closures against outward movement, means for disengaging said locking means of the lower closure when the dipper is turned into unloading position, a 110 support for said arm having universal connection therewith, and operating mechanism adapted to reciprocate said arm transversely or obliquely to the machine.

In testimony whereof I have hereunto set 115 my hand in presence of two subscribing witnesses.

CHRISTIAN H. KREILING.
